ALOYSIUS J. ABELS, OF BUFFALO, NEW YORK, ASSIGNOR TO HANDI-APPLIANCE CORPORATION, OF BUFFALO, NEW YORK, A CORPORATION OF NEW YORK

FLUID-PRESSURE MOTOR

Application filed April 28, 1926. Serial No. 105,292.

This invention relates to a fluid pressure motor for a washing machine which is operated by means of fluid pressure such as the water pressure taken from a city water supply faucet and which is more particularly intended for washing small articles or clothing and the like.

The principal difficulty which has heretofore been experienced with machines of this character is that the valve mechanism was not sensitive and would not respond readily and reliably to the pressure of the water. In the present case the valve operating mechanism is very sensitive and operates very quickly and reliably in shifting the valve near the opposite ends of the stroke of the pistons.

The method of mounting the valve also relieves the same from undue pressure of the water in the valve chamber so that the valve is not liable to stick against its seat and fail to operate when an abnormal pressure of water is exerted against the same. Such abnormal pressure of water is apt to occur when no water is used elsewhere in the building, such for example in an apartment house, or if a number of tenants at the same time turn off the water and thereby cause a sudden increase in pressure on the valve mechanism of the respective washing machine.

Moreover this washing machine as a whole has no delicate parts which are liable to get out of order, all of its several parts are readily accessible for inspection, cleaning and lubrication and the same are arranged compactly so as to occupy a minimum space which permits of using the same in smaller quarters and also stowed away conveniently when not in use.

It is the object of this invention to provide a machine of this character which is comparatively simple in construction, efficient in operation, low in cost of manufacture and capable of working with a minimum pressure without liability of getting out of order or ceasing to function when the pressure of the fluid under which it operates changes from one degree to another.

In the accompanying drawings:

Figure 1 is a vertical longitudinal section of a fluid operated motor embodying my improvements.

Figure 2 is a horizontal section of the valve mechanism taken on line 2-2 Fig. 1.

Figure 3 is a fragmentary section on an enlarged scale, taken on line 3-3, Fig. 2 and looking forwardly.

Figure 4 is a view similar to Fig. 1 but showing the valve shifting pistons nearing the end of the stroke to the right and about to trip the valve mechanism so as to reverse the water pressure.

Figure 5 is a similar view showing the valve mechanism completely reversed from the position shown in Fig. 1.

Figure 6 is a horizontal section similar to Fig. 2 but showing the valve mechanism reversed and taken on line 6-6, Fig. 5.

Figure 7 is a vertical section taken on line 7-7, Fig. 6 and showing the valve tappets of the valve mechanism reversed as compared with the position shown in Fig. 3.

Figure 8 is a vertical section taken on line 8-8, Fig. 1.

Figure 9 is a vertical section taken on line 9-9, Fig. 8.

Figure 10 is a vertical section taken on line 10-10, Fig. 5.

Figure 11 is a horizontal section taken on line 11-11, Fig. 8.

Figure 12 is a perspective view of the fluid pressure reversing valve.

Figure 13 is a fragmentary section similar to Fig. 8, showing a modification of the means for holding the main shaft against longitudinal movement.

Figure 14 is a fragmentary section of the central part of the tube forming the passages to the ends of the cylinders.

Similar characters of reference indicate like parts in the several views.

Although this fluid operated motor may be utilized for operating any part which requires oscillation, the same is shown in the present case in connection with the rocking drum 23 of a washing machine which is provided at one end with a trunnion 28 which turns in a bearing 30 on the adjacent wall 19 of a casing or tank, which bearing formed

on a frame 70 is arranged outside of the casing and connected therewith by screws 71 passing through washers 73 interposed between the casing and the frame, as shown in Fig. 11.

5 The drum is oscillated in the tank by a fluid pressure motor which is constructed as follows:

The numeral 31 represents a rock shaft 10 journaled in an outward extension of the bearing 30 and provided at its inner end with a longitudinal slot 32 forming a coupling fork which receives the flat surfaces 33 on the trunnion so that the same in effect 15 forms a key or flat tang, and at its outer end the same is provided with a pinion 34 which meshes with a horizontally reciprocating gear rack 35. This shaft is free to turn in the bearing 30 but is held against lengthwise 20 movement therein by means of a key 73 having preferably the form of a plate which is detachably secured to the tank end wall 19 by means of two of the screws 71 and engaging this key with the upper part of an annular 25 groove 74 in the periphery of the shaft adjacent to the outer end of the longitudinal slot 32 therein, as shown in Figs. 8 and 9. In these figures of the drawings the key is arranged on the outer side of the tank, but in 30 Fig. 13 the same is arranged on the inner side of the tank, the function in both cases however being the same. At opposite ends this gear rack is provided with pistons 36 which reciprocate in cylinders 37, 38 formed on the 35 frame 70. Water under pressure from any source, such as from the faucet of a kitchen sink, is admitted alternately to the outer ends of the cylinders 37 and 38 and also exhausted alternately from these cylinders for the purpose of producing a reciprocating effect on 40 the gear rack 35.

Water for this purpose is supplied by a pipe or hose 39 to a valve chamber 40 which latter is arranged on the frame 70 below the gear pinion and the opposing inner ends 45 of the motor cylinders and has a main or pressure port 41 leading by means of a conduit 42 to the outer end of the cylinder 37, a main or pressure port 43 leading by a conduit 44 to the outer end of the cylinder 38, and an exhaust port 45 between the ports 41 and 43. The pressure ports 41, 45 are alternately connected with the valve chamber 40 and with the exhaust port 45 by means of a slide valve 46 which is constructed 50 in the form of a cup and moves with its hollow or concave side in engagement with a valve seat 47 on the rear side of the valve chamber. The front section or wall 75 of 55 the valve chamber is removably connected by screws 76 with the rear part of this chamber, and the hose 39 supplying the fluid under pressure is connected with the lower part of this wall, as shown in Figs. 3 and 8. In 60 Figure 2 the valve 46 is shifted to the right so

as to connect the left pressure port 41 with the valve chamber and admit water under pressure to the outer end of the cylinder 37 and at the same time the exhaust port 45 is connected with the right pressure port 43 leading to the outer end of the cylinder 38 so as to permit the spent water in the latter to escape to a drain passage 48 which is arranged in the frame in rear of the valve chamber and connects at its upper end with the exhaust port while its lower end connects with a hose 77 leading to the drain or sink.

70 The distributing conduits 42, 44 are preferably formed by means of a small tube or pipe which is bent into shape and compressed at its center to form a partition 78 which separates the tube into two sections constituting the conduits 42, 44 and then placing the pipe or tube in the mold in which the casting is produced constituting the frame and cylinders. After this tube has been thus embedded in the casting the latter is bored or drilled to form the pressure ports 41, 43 leading from the valve seat to the inner ends of the tube sections, and the casting and compressed partition or central part 78 of this tube is bored to form the exhaust port 45 leading from the valve seat to the upper end of the drain passage 48.

75 The valve 46 is yieldingly held against its seat by means of a slotted spring bar or plate 49 which receives a stem or pin 50 projecting forwardly from this valve, as shown in Figs. 1, 2 and 8.

80 In order to prevent the fluid under pressure in the valve chamber from pressing the valve against its seat so heavily as to interfere with its free movement this valve is made of horizontally elongated form as shown best in Fig. 12, and made of a width substantially the same as the guide bar or plate 49 so that the latter covers the valve and protects the same against undue pressure, whereby easy and positive working of the valve is insured regardless of an abnormally high pressure 85 in the valve chamber. The valve is retained in this position by providing the front side of the same around its stem or pin 50 with a flat sided neck or shoulder 79 which works in the slot 80 of the plate 49 in the manner of a spline which prevents the valve from turning but permits the same to move lengthwise.

90 In Figure 6 the valve 46 is shown reversed or moved to the left so as to exhaust the spent water from the cylinder 37 and permit water 95 under pressure to enter the cylinder 38.

100 The valve is shifted alternately into these positions by means of two valve tappets 51, 52 which are mounted on the rear end of a horizontal rock shaft 53, these tappets being spaced far enough apart so that an idle motion occurs in the same during which the valve remains at rest in either of its extreme 105 positions, but when the pistons effect the last part of their motion in one direction 110

the right tappet 51 will engage the stem 50 of the valve and shift the same toward the left, as shown in Fig. 7, and when the left tappet 52 moves in the opposite direction the latter will engage the valve stem 50 on the other side, as shown in Fig. 3 and move the valve in the opposite direction.

The rocking movement of the tappets 51 and 52 is effected by motion which is derived from the gear rack 35 by the following means:

The numeral 54 represents an upper trip rock lever which is pivoted concentrically with the axis of the gear pinion 35, and 55 represents a lower main rock lever which is secured to the front end of the shaft 53 of the tappets. The upper or trip lever 54 is preferably pivoted on a pin 81 on the front end of the gear pinion shaft by means of a bushing or ferrule 82 inserted in this lever and turning on this pin, thereby obtaining an increased bearing surface and insuring longer wear. The outer arms of the upper and lower levers are connected by means of a spring 56 and the inner arms thereof are connected by means of a coupling pin 57 which is adapted to slide lengthwise in slots 58, 85 in the opposing inner arms of the levers 54 and 55 and also projects through a longitudinal slot 59 in a plate or bar 60 arranged in front of the gear rack.

The coupling pin 57 is held against axial displacement by means of a head 83 at its rear end sliding lengthwise in a guideway 35 formed between the bar or plate 60 and another bar or plate 84 arranged in rear of the front plate 60, these plates being spaced apart and secured at their ends to the front side of the gear rack, as shown in Figs. 8 and 11.

In Figure 1 the pistons are at the left of the cylinders and the outer arms of the rock levers 54 and 55 are swung to the right and retained in this position by means of the spring 56, and the valve 46 is at the right end of its movement at which time the water under pressure is admitted to the left cylinder 37 and the spent water is exhausted from the right cylinder 38. The parts of the valve mechanism remain in this position until the pistons have moved far enough to the right to cause the left hand end of the slot 59 acting as a tappet to engage the shifting pin 57 and carry the same from the left hand side 55 of the dead center of the valve mechanism to a point slightly beyond the dead center in the opposite direction, as shown in Fig. 4. When this occurs the outer arms of the rock levers 54, 55 have been carried beyond the dead center to the right, whereupon the resilience of this spring 56 quickly completes the throw of the levers 54 and 55 in this direction and carries the coupling pin 57 away from the left hand tappet end of the slot 59 and causes the tappet 51 to engage with the

valve stem 50 and move the valve into its extreme left hand position, as shown in Figs. 5, 6 and 7, whereby the flow of the live and dead pressure medium is reversed so that the pistons will be moved from right to left and the gear rack and pinion are caused to turn the drum in the opposite direction.

During the first part of the subsequent motion of the pistons and rack from right to left no effect is produced on the valve mechanism and the valve remains at rest, due to the spacing apart of the tappets at opposite ends of the slot 59, but during the last part of this movement of the pistons the rock levers 54 and 55 are turned so that their outer arms swing toward the right due to the right hand end of the slot 59 acting as a tappet against the coupling pin 57 and thereby strain the spring 56. When these levers have moved slightly beyond the dead center toward the right this spring 56 again completes the throw of these levers 54, 55 independently of the gear rack and by quick motion, thereby causing the tappet 52 to shift the valve in the opposite direction and again reverse the flow of the water under pressure and the exhaust water so as to cause the drum to be rocked in the opposite direction. By spacing apart the tappets 51, 52 the period of time during which the valve may remain at rest is extended without making the slot 59 unduly long and also without requiring the pistons and gear rack to travel so far as would make the apparatus unnecessarily wide and bulky. This operation is repeated continuously and a rocking motion is imparted to the drum so long as the water is turned on. The rocking movement of the levers may be limited in any suitable manner, for example by stops 86, 86 arranged on the front wall of the valve casing and adapted to be engaged by the main rock lever as shown in Fig. 6.

I claim as my invention:

1. A fluid pressure motor comprising a gear pinion, a reciprocating gear rack meshing with said pinion, pistons arranged on said rack, a frame provided with cylinders which receive said pistons, a conducting tube arranged in said frame and composed of two sections communicating at their outer ends with the corresponding ends of said cylinders and the central part of said tube being pressed together to form a partition between said tube sections and the inner ends of said sections being provided with openings, a valve chamber arranged on said frame and provided with an inlet for a pressure medium, main ports communicating with said openings and an exhaust port, and a slide valve arranged in said valve chamber and connecting said main ports alternately with said valve chamber and said exhaust port.

2. A fluid pressure motor comprising a

gear pinion, a reciprocating gear rack meshing with said pinion, pistons arranged on said rack, a frame provided with cylinders which receive said pistons, a conducting tube arranged in said frame and composed of two sections communicating at their outer ends with the corresponding ends of said cylinders and the central part of said tube being pressed together to form a partition between said tube sections and the inner ends of said sections being provided with openings, a valve chamber arranged on said frame and provided with an inlet for a pressure medium, main ports communicating with said openings and an exhaust port, and a slide valve arranged in said valve chamber and connecting said main ports alternately with said valve chamber and said exhaust port, said compressed part of the tube being provided with a transverse opening forming part of an exhaust passage which communicates with said exhaust port.

3. A fluid pressure motor comprising a gear pinion, a gear rack meshing with said pinion, pistons arranged on said gear rack, cylinders which receive said pistons, a valve chamber having an inlet for a pressure medium, main ports communicating with the opposite ends of said cylinders and an exhaust port, a slide valve arranged in the valve chamber and adapted to connect said main ports alternately with said valve chamber and said exhaust port, and means for shifting said valve comprising a pair of spaced valve tappets adapted to shift said valve in opposite directions, a main rock lever connected with said tappets and having inner and outer arms, a trip lever having inner and outer arms, widely spaced apart tappets on said gear rack adapted to shift said levers in opposite directions, and a spring connecting the outer arms of said levers.

4. A fluid pressure motor comprising a gear pinion, a gear rack meshing with said pinion, pistons arranged on said gear rack, cylinders which receive said pistons, a valve chamber having an inlet for a pressure medium, main ports communicating with the opposite ends of said cylinders and an exhaust port, a slide valve arranged in the valve chamber and adapted to connect said main ports alternately with said valve chamber and said exhaust port, and means for shifting said valve comprising a pair of spaced valve tappets adapted to shift said valve in opposite directions, a main rock lever connected with said tappets and having inner and outer arms, a trip lever having inner and outer arms, the inner arms of said levers having longitudinal slots, a pin passing through said slots, spaced lever tappets arranged on said rack bar and adapted to engage opposite sides of said pin, a spring connecting the outer arms of said levers and a bar arranged lengthwise on said gear rack and provided with a longitudinal slot the sides of which form a guideway for said pin and the ends of which form said lever tappets.

5. A fluid pressure motor comprising a gear pinion, a gear rack meshing with said pinion, pistons arranged on said gear rack, cylinders which receive said pistons, a valve chamber having an inlet for a pressure medium, main ports communicating with the opposite ends of said cylinders and an exhaust port, a slide valve arranged in the valve chamber and adapted to connect said main ports alternately with said valve chamber and said exhaust port, and means for shifting said valve comprising a pair of spaced valve tappets adapted to shift said valve in opposite directions, a main rock lever connected with said tappets and having inner and outer arms, a trip lever having inner and outer arms, the inner arms of said levers having longitudinal slots, a pin passing through said slots, spaced lever tappets arranged on said rack bar and adapted to engage opposite sides of said pin, a spring connecting the outer arms of said levers and a bar arranged lengthwise on said gear rack and provided with a longitudinal slot the sides of which form a guideway for said pin and the ends of which form said lever tappets.

6. A fluid pressure motor comprising a gear pinion, a gear rack meshing with said pinion, pistons arranged on said gear rack, cylinders which receive said pistons, a valve chamber having an inlet for a pressure medium, main ports communicating with the opposite ends of said cylinders and an exhaust port, a slide valve arranged in the valve chamber and adapted to connect said main ports alternately with said valve chamber and said exhaust port, and means for shifting said valve comprising a pair of spaced valve tappets adapted to shift said valve in opposite directions, a main rock lever connected with said tappets and having inner and outer arms, a trip lever having inner and outer arms, the inner arms of said levers having longitudinal slots, a pin passing through said slots, spaced lever tappets arranged on said rack bar and adapted to engage opposite sides of said pin, a spring connecting the outer arms of said levers and a bar arranged lengthwise on said gear rack and provided with a longitudinal slot the sides of which form a guideway for said pin and the ends of which form said lever tappets.

7. A fluid pressure motor comprising a gear pinion, a gear rack meshing with said pinion, pistons arranged on said gear rack, cylinders which receive said pistons, a valve chamber having an inlet for a pressure medium, main ports communicating with the opposite ends of said cylinders and an exhaust port, a slide valve arranged in the valve chamber and adapted to connect said main ports alternately with said valve chamber and said exhaust port, and provided with an outward projection, a guide bar provided with a longitudinal slot which receives said projection, and means for shifting said valve by motion derived from said gear rack.

8. A fluid pressure motor comprising a

- gear pinion, a gear rack meshing with said pinion, pistons arranged on said gear rack, cylinders which receive said pistons, a valve chamber having an inlet for a pressure medium, main ports communicating with the opposite ends of said cylinders and an exhaust port, a slide valve arranged in the valve chamber and adapted to connect said main ports alternately with said valve chamber and said exhaust port, and provided with an outward projection, a spring guide bar mounted in the valve chamber and receiving said projection and holding said valve resiliently against the surface of said chamber containing said ports and provided with a slot which receives said projection, and means for shifting said valve cooperating with said gear rack and said projection.
9. A fluid pressure motor comprising a gear pinion, a gear rack meshing with said pinion, pistons arranged on said gear rack, cylinders which receive said pistons, a valve chamber having an inlet for a pressure medium, main ports communicating with the opposite ends of said cylinders and an exhaust port, a slide valve arranged in the valve chamber and adapted to connect said main ports alternately with said valve chamber and said exhaust port, and means for shifting said valve comprising a pair of spaced valve tappets adapted to shift said valve in opposite directions, a main rock lever having outer and inner arms and having its axis connected with said lever tappets, a trip lever having inner and outer arms and pivoted concentrically with said gear pinion and its shaft, means engaging the inner arms of said levers for shifting the same by motion derived from said rack, and a spring connecting the outer arms of said levers.
10. A fluid pressure motor comprising a gear pinion, a gear rack meshing with said pinion, pistons arranged on said gear rack, cylinders which receive said pistons, a valve chamber having an inlet for a pressure medium, main ports communicating with the opposite ends of said cylinders and an exhaust port, a slide valve arranged in the valve chamber and adapted to connect said main ports alternately with said valve chamber and said exhaust port, and means for shifting said valve comprising a pair of spaced valve tappets adapted to shift said valve in opposite directions, a rock shaft carrying at its rear end said valve tappets, a main rock lever connected with the front end of said rock shaft and having inner and outer arms, a trip lever pivoted concentrically with said gear pinion and having inner and outer arms, means for producing a limited sliding connection between the inner arms of said levers and said gear rack, and a spring connecting the outer arms of said levers and operating to quickly complete the throw of said

levers after they have been moved past the dead center.

In testimony whereof I hereby affix my signature.
